Primary Examiner — Patricia Palasik(74) *Attorney, Agent, or Firm* — Holtz, Holtz, Goodman & Chick PC(57) **CLAIM**

The ornamental design for a sheet holder for stamp making machine, as shown and described.

DESCRIPTION

FIG. 1 is a front, right side, top perspective view of a sheet holder for stamp making machine showing our new design; FIG. 2 is a front elevational view thereof; FIG. 3 is a rear elevational view thereof; FIG. 4 is a left side view thereof; FIG. 5 is a right side view thereof; FIG. 6 is a top plan view thereof; FIG. 7 is a bottom plan view thereof; and, FIG. 8 is a reference view thereof showing a using state. The portions in broken lines are shown for illustrative purposes only and form no part of the claimed design.
